UNITED STATES PATENT OFFICE.

CHARLEY R. HELLEIN, OF GREENSBURG, PENNSYLVANIA.

DISPENSING APPARATUS.

1,238,405.

Specification of Letters Patent.

Patented Aug. 28, 1917.

Application filed December 4, 1916. Serial No. 134,978.

To all whom it may concern:

Be it known that I, CHARLEY R. HELLEIN, a citizen of the United States, residing at Greensburg, in the county of Westmoreland and State of Pennsylvania, have invented certain new and useful Improvements in Dispensing Apparatus, of which the following is a specification.

This invention relates to devices for supplying lubricant to bearings and other parts of automobiles or other machinery which are generally treated with lubricants of a rather heavy consistency.

The object of the invention is to provide a simple apparatus by the use of which the lubricant will be provided or stored in such manner that it can be easily handled without coming in direct contact with the hands or clothes of the user.

20 And a further object of the invention is to provide simple means whereby the lubricant may be applied directly to the parts needing lubrication.

The invention is illustrated in the accompanying drawings, in which:

Figure 1 is an elevation of my improved apparatus;

Fig. 2 is a vertical section of the same;

Fig. 3 is a plan view of the can or receptacle in which the lubricant is stored;

Fig. 4 is a detail perspective view of a lifter which may be provided to effect withdrawal of the plunger or cap which is fitted within the can or tank and bears directly upon the body of the lubricant.

In carrying out my invention, I employ a can or tank 1 which is preferably constructed with a conical bottom 2 so that the lubricant will be prevented from collecting in the bottom of the can in such form that it cannot be withdrawn. The top or upper end of the can is open, and in the said upper end I fit a plunger 3 which is in the form of a ring having a conical body 4 rising from its lower edge and extending through the ring and above the upper edge of the same. The apex of the cone is removed and a nozzle 5 formed theret. The ring 3 should be of such an external diameter that it will fit closely within the can or tank 1 but may descend within the can or tank as the lubricant is withdrawn. Upon the upper surface of the conical body 4 I provide the offsets 6 which may conveniently be formed of sheet metal bent to the

proper shape and secured rigidly to the body 4 and the nozzle or spout 5, as clearly shown in Fig. 2. These offsets provide stops to limit the extent to which the extractor 7 may be inserted over the nozzle 5 and also provide means to be engaged by the lifter 8 when it is desired to withdraw the plunger or follower from the can.

It will be noted, upon reference to Fig. 4, that the lifter 8 is formed by doubling a stout wire and twisting the branches of the same upon each other so as to provide a shank having a handle member 9 at one end and having spaced fingers 10 at the opposite end. The fingers 10 may be engaged under the offsets 6 at opposite sides of the nozzle or spout 5 and the plunger or follower thereby readily withdrawn from the can or tank.

The extractor 7 may be of any well known construction, comprising a cylindrical body having a reduced end 11 forming a spout which may be engaged over the nozzle or spout 5 and fitted snugly thereon. The piston 12, within the cylindrical body, is secured upon a piston rod 13 which extends through the upper end of the cylinder and is equipped with a handle 14, as will be readily understood.

It is thought the manner of using my device will be readily understood from the foregoing description taken in connection with the accompanying drawings. The can or tank 1 is filled with the lubricant and the plunger or follower then fitted in the upper end of the tank so as to rest directly upon the lubricant. Preferably, the plunger will be pressed down onto the lubricant so that the lubricant will fill the conical body of the follower. The extractor 7 is fitted upon the spout or nozzle 5, as shown in the drawings, with the piston 12 at the end of the cylinder forming the spout 11. By holding the cylinder stationary and against the follower, while drawing the piston away from the spout 11, the lubricant will be drawn into the cylinder so as to fill the same. When the cylinder has been filled, it is detached from the follower and the lubricant will remain therein until the extractor 7 has been carried to or placed directly upon the bearings or other part to be lubricated whereupon the piston will be operated to expel the lubricant, as will be readily understood. As the supply of lubricant is

consumed, the follower will, of course, be pressed farther into the tank or can and at the lowest extremity or bottom of the can will fit over the conical bottom 2 in 5 such a manner that the lubricant will be forced up into the follower and every particle thereof may be withdrawn from the can.

My device is exceedingly simple in the 10 construction and arrangement of its parts, may be manufactured at a low cost and will be found highly efficient when in use.

Having thus described the invention, what 15 is claimed as new is:

An apparatus for the purpose set forth comprising a receptacle having a conical

bottom, a follower fitting closely within the receptacle and having a conical body adapted to rest on the conical bottom of the receptacle, a nozzle projecting upwardly 20 from the apex of the conical body, a cylinder having its lower end adapted to fit snugly upon said nozzle, a piston working in said cylinder, and off-sets projecting laterally from the nozzle on the follower at 25 opposite points of the same to limit the engagement of the cylinder over the nozzle, the off-sets being spaced from the conical body of the follower whereby they may be engaged by a lifting device.

In testimony whereof I affix my signature.

CHARLEY R. HELLEIN. [L.S.]
